COMBINED TOY ROCKET PROJECTILE AND
LAUNCHER OR SIMILAR ARTICLE

Robert J. Johnson, Richmond, Va., assignor, by mesne
assignments, to Scientific Products Company, Rich-
mond, Va., a corporation of Virginia

Filed Mar. 25, 1958, Ser. No. 50,172

Term of patent 14 years

(Cl. D34—15)

~~FIG~~ 4.Fig. 1 is a front perspective view of the combined toy rocket projectile and launcher or similar article;

Fig. 2 is a rear elevational view;

Fig. 3 is an exploded view; and

Fig. 4 is a top plan view of the rocket portion only.

The essential features of my design reside in the portions shown in full lines.

I claim:

The original design for a combined toy rocket projectile and launcher or similar article, substantially as shown and described.
